UNITED STATES PATENT OFFICE.

WALTER I. KIRK, OF CHICAGO, ILLINOIS, ASSIGNOR TO LYON & HEALY, OF CHICAGO, ILLINOIS, A CORPORATION OF ILLINOIS.

PEDAL FOR MUSICAL INSTRUMENTS.

1,173,811.

Specification of Letters Patent. Patented Feb. 29, 1916.

Application filed June 26, 1914. Serial No. 847,409.

To all whom it may concern:

Be it known that I, WALTER I. KIRK, a citizen of the United States, residing at Chicago, in the county of Cook and State 5 of Illinois, have invented a certain new and useful Improvement in Pedals for Musical Instruments, of which the following is a full, clear, concise, and exact description, reference being had to the accompanying 10 drawings, forming a part of this specification.

My invention relates to pedals, and especially to pedals for musical instruments such, for example, as harps or other similar 15 instruments.

The principal object of the invention is to provide a simple, practical and advantageous construction of pedal of the general class specified.

20 Another object is to secure an easy and comfortable touch for the foot in using the pedal, and to prevent the foot from slipping.

A further object is to secure durability and simplicity, and also to permit replacement 25 of a worn portion of the pedal, so as to increase the length of life of the pedal proper, and for other purposes.

Further objects of the invention are to secure a high degree of efficiency and excellency in construction and to secure the foregoing and other desirable results in a simple and expeditious manner.

In the accompanying drawings—Figure 1 30 is a harp having a pedal embodying my invention; Fig. 2 is a longitudinal section of said pedal; Fig. 3 is a cross-section taken on line 3—3 of Fig. 3; Fig. 4 is a top plan of an end of the pedal with a detachable cap thereon, and Fig. 5 is a top view of a portion 40 of the cap.

The pedal which I show herein for carrying out my invention involves a top portion 1 and downwardly-extending side portions 2 and 3, which side portions are preferably 45 united at the end of the pedal by a band portion 4 conveniently formed continuously and integrally with the side portions 2 and 3.

A cap 5 is mounted upon the outer end 50 portion of the pedal, as shown in Fig. 2. Said cap 5 is preferably made at least in part of elastic or cushion-like material such as rubber, and is also preferably detachably secured to the end portion of the pedal, so 55 that the cap forms a cushionlike abutment

or part upon which the foot may rest and against which it may press, and also that this cap may be detached and replaced by a new one if desired.

In the construction which I show herein, 60 the cap 5 is preferably made with a base portion 6 of metal and an upper portion 7 of cushionlike material, such as rubber or rubber composition, or the like. The base portion 6 fits closely upon the end portion 65 of the pedal, and as a preferred arrangement in order to maintain the cap firmly in position, the metal base portion 6 is made with side flanges 8, 8, so that said portion 6 substantially incloses and fits snugly upon and 70 around the end portion of the pedal. As a preferred construction also, the end portion of the pedal is depressed as at 9, and the cap member or base 6 is also correspondingly extended downward, so that satisfactory fit 75 and an abutment is formed as between the cap and pedal, as well shown in Fig. 2. The cap may be made detachable from the pedal in any preferred way, but as a convenient arrangement I provide the end portion of 80 the pedal with an aperture and pass a screw 10 through the same and into an aperture in the metal member 6 of the cap 5. The head of this screw 10 is underneath the pedal and so out of sight, although it is readily accessible whenever desired, to loosen and remove the cap.

The member 6 is preferably provided with punched-out apertures 11, 11 (Fig. 5), so that a firm engagement between the member 90 6 and the cushion portion 7 will be secured. As a preferred arrangement, the cushion member 7 is made of rubber properly vulcanized upon the member 6.

Thus, it will be seen that the cap may be 95 easily and inexpensively constructed and may be quickly applied in a detachable manner to the end portion of the pedal; also, that when so applied, the cap forms a cushion which is very comfortable to the 100 foot and also affords satisfactory engagement for the foot so that the latter will not slip. Furthermore, it will be seen that the cap will have a firm and substantial grip on the pedal, so that it will not be readily 105 displaced, and that when desired to remove it for replacement by a new cap or for other purposes, it may be quickly detached and then the old or another similar cap replaced.

It will be understood that changes and 110

modifications may be made without departing from the spirit of the invention.

What I claim is:—

1. A pedal provided with a cap device comprising a base member constructed to fit the end portion of the pedal, said pedal having end portions which are disposed in different planes with relation to each other, and a cushion portion secured to said base portion above the same, and a screw passing through the pedal and into the base portion of the cap device.
2. A pedal provided with a cap device comprising a base portion adapted to fit the end portion of the pedal and having downwardly-extending flanges adapted to fit against the sides of the pedal, said flange conforming in shape to the side walls of the pedal, and a cushion portion secured to and mounted above said base portion, and means for detachably securing said cap device to the end portion of the pedal.
3. A pedal provided with a cap device comprising a base member constructed to fit the end portion of a pedal, said base portion being provided intermediate its ends with a shouldered portion, a cushion provided upon said base member, and the upper side portion of said cushion being comparatively flat.
4. A pedal provided with a cap device comprising a base member constructed to fit the end portion of a pedal, said base portion being provided intermediate its ends with a shouldered portion, a cushion provided upon said base member, and means for detachably securing said cap device to the pedal.
5. In a pedal cap in combination, a mem-

ber constructed to fit the end portion of a 40 pedal, said member having a downwardly depending flange, forming an opening in the underside of said member, said opening corresponding to the size of the pedal, and said flange being open at an end, and means 45 for securing said cap to said pedal.

6. A pedal provided with a cap device comprising a base member constructed to fit the end portion of the pedal, said base member being channeled and open at an end, the 50 respective ends of said base member being disposed in different planes with relation to each other, a cushion portion provided upon said base member, the under side of said cushion conforming to the upper side of 55 said base portion, and the upper side portion of said cushion being flat.

7. A cap device for pedals comprising a metallic base portion, a cushion provided upon said base portion, said base portion 60 having upwardly extending portions which extend into the cushion, and a downwardly extending flange provided upon said base portion which extend beyond said cushion.

8. A cap device for pedals comprising a 65 metallic base portion having a downwardly extending flange provided upon an end and both sides, a cushion provided upon said base portion, said base portion being apertured to receive a screw and having upwardly extending portions engaging said cushion.

In witness whereof, I hereunto subscribe my name this 22nd day of June, A. D., 1914.

WALTER I. KIRK.
